UNITED STATES PATENT OFFICE.

BURL V. ROSE, OF RIDGEWAY, OHIO.

LUBRICATOR.

1,246,469.

Specification of Letters Patent. Patented Nov. 13, 1917.

Application filed May 12, 1917. Serial No. 168,195.

To all whom it may concern:

Be it known that I, BURL V. ROSE, a citizen of the United States, residing at Ridge-way, in the county of Hardin and State of 5 Ohio, have invented certain new and useful Improvements in Lubricators, of which the following is a specification.

This invention relates to lubricators, and more particularly to a mechanically operated lubricator designed for use on reciprocating parts of machinery that require profuse lubrication and, by reason of their movement, are dangerous to lubricate by the ordinary hand lubricator.

One of the objects of the invention is to provide a grease cup of the plunger type, the stem of the plunger being provided with serrations to form a rack bar, while the body of the cup is provided with mechanically operated means for imparting movement to the plunger, so that the grease within the container or cup may be ejected in the required quantity.

A further object of this invention is the provision of a lubricator which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, 35 wherein is illustrated the preferred form of my invention, in which;

Figure 1 is a side elevation of the device constructed in accordance with my invention.

Fig. 2 is a fragmentary vertical section therethrough.

Fig. 3 is a detail vertical section.

Fig. 4 is a detail horizontal section.

Fig. 5 is a section taken substantially on 45 the line 5—5 of Fig. 1.

Referring to the drawing, wherein is illustrated the preferred form of my invention, and in which like numerals of reference indicate corresponding parts throughout the several views, the grease cup 1 is provided with a stem 2 having a screw threaded portion 3 for mounting the cap upon the part of the machinery which is to be lubricated. The upper end of the cup 55 is screw threaded to receive a cap 4 pro-

vided with a central circular opening 5. Within the cup is a plunger 6 for engagement with the grease or oil carried by the cup, whereby the grease or oil may be ejected from the cup when the plunger is actuated. Secured to the plunger is a plunger rod which extends upwardly through the opening 5 in the cap, and this plunger rod has teeth or serrations thus forming a rack bar 7 of the plunger rod.

Fastened to the cap 4 in any preferred manner is a casing 8 having a central opening in its top through which the rack bar 7 projects. Extending through the casing 8, and journaled in the sides thereof, as shown by Fig. 5 of the drawing, is a shaft 9 having a tooth 10 formed thereon for engaging the teeth of the rack bar 7, so that when the shaft 9 is rotated, the rack bar will be actuated either upwardly or downwardly according to the direction of rotation of the shaft 9. The outer end of the shaft 9 carries a gear 11.

Detachably mounted on the side of the cup 1 is a gear box 12 which is closed on all sides except the side engaging the body of the cup, so that when the gear case box is mounted in position, the side of the cup 1 will form one side of the gear box as shown to advantage in Fig. 2 of the drawing. The upper and lower walls of the gear box are cut out as indicated at 13 in Fig. 4, so that the upper and lower walls will fit snugly around the cup and the gear case is then attached by a band 14 embracing the gear case, and the cup 1 and joined together at its ends by a bolt 15.

Disposed vertically within the gear case 12 and journaled in the upper and lower walls thereof is a countershaft 16, the upper end of which carries an eccentric worm 17 in mesh with the teeth of the gear 11; this worm being designed to impart movement to the gear 11 equal to the length of the circular pitch upon each revolution of the eccentric worm 17. Within the gear case, the shaft 16 carries a pinion 18 in mesh with a single tooth 19 of a crown gear 20, the latter being mounted on a stud shaft 21 journaled in the outer wall of the gear case 12. This single tooth carried by the crown gear meshes with the teeth of the gear 18, so that one revolution of the crown gear will impart merely a partial movement to the shaft 16, the ratio being preferably 16 to 1, so

that the crown gear must rotate 16 times to impart a single rotation of the gear 18.

Transversely mounted in the gear case and extending across the crown gear is a drive shaft 22, and this shaft is provided with a single tooth 23, in mesh with the teeth of the crown gear which may be provided with any number of teeth so that each revolution of the shaft 22 will impart a movement to the crown gear equal to the distance between the teeth. Mounted on the outer end of the shaft 22 is a star wheel 25, the radiating fingers of which are adapted to engage a convenient projection or machinery part, so that the wheel will be rotated when it engages the said projection upon the reciprocation or movement of the part of the machinery to which the lubricator is attached. It will be seen, therefore, that the star wheel will impart movement to the shaft 22, and the latter, through the medium of the tooth 23 will impart movement to the crown gear 20. The crown gear, by having a single tooth 19 engage with the gear 18, will impart rotary movement to the shaft 16 which carries the gear 18. The eccentric worm 17, carried by the shaft 16 at the exterior of the gear case, will turn the shaft 9 through the medium of the gear 11, and this shaft, in turn, will actuate the rack bar to force the piston downwardly within the lubricator for ejecting the lubricant. This construction will cause a very slight movement of the piston when the machinery is moving at a great rate of speed, and it will be apparent that the gear box may be quickly and easily removed by detaching the band 14, so that gears of different sizes and different pitches may be placed within the gear box to vary the speed of movement of the plunger 6 according to the speed of the machinery to which the lubricator is attached. Thus, the lubricant may be adjusted to the exact degree required.

From the foregoing it will be observed that a very simple and durable lubricator has been provided, the details of which embody the preferred form. I desire it to be understood, however, that slight changes in the minor details of construction may be made without departing from the spirit of the invention or the scope of the claims hereunto appended.

55. I claim:

1. The combination with a grease cup, of a casing mounted on the top of the grease cup, a plunger mounted in the grease cup for sliding movement, a rack bar attached to said plunger, a gear case detachably connected to the side of the grease cup, and means mounted in the casing and in the gear case to engage the rack bar for im-

parting movement to the latter when the said means is actuated.

65

2. The combination with a grease cup, of a casing mounted thereon, a grease cup having a plunger provided with a rack bar extending through the top of the grease cup and through the said casing, a gear case detachably connected to the side of the grease cup, a shaft mounted in the casing and having a single tooth engageable with the rack bar, one end of the shaft being extended over the casing above the said gear case and carrying a gear, and means mounted in the gear case and engageable with the said gear to actuate the shaft, whereby movement may be imparted to the said plunger.

70

3. The combination with a grease cup, of a casing mounted thereon, a grease cup having a plunger provided with a rack bar extending through the top of the grease cup and through the said casing, a gear case detachably connected to the side of the grease cup, a shaft mounted in the casing and having a single tooth engageable with the rack bar, one end of the shaft being extended over the casing above the said gear case and carrying a gear, a shaft journaled in the sides of the gear case and projecting from one side thereof, a star wheel mounted on the extended end of the last mentioned shaft, and means carried by the gear case and engageable with the said gear whereby movement may be imparted to the plunger when the star wheel is actuated.

75

4. The combination with a grease cup, of a casing mounted thereon, a grease cup having a plunger provided with a rack bar extending through the top of the grease cup and through the said casing, a gear case detachably connected to the side of the grease cup, a shaft mounted in the casing and having a single tooth engageable with the rack bar, one end of the shaft being extended over the casing above the said gear case and carrying a gear, a shaft journaled in the sides of the gear case and projecting from one side thereof, a star wheel mounted on the extended end of the last mentioned shaft, a counter-shaft mounted in the gear case and disposed at right angles to the other shaft in the gear case and projecting from the top thereof, an eccentric worm carried by the end of the counter-shaft and engaged with the said gear, and means mounted within the gear case and co-operating with the shafts therein to turn the said eccentric worm when the star wheel is actuated.
